UNITED STATES PATENT OFFICE.

PATRICK J. GRIFFIN, OF DORCHESTER, MASSACHUSETTS.

PROPELLER.

1,360,933.

Specification of Letters Patent. Patented Nov. 30, 1920.

Application filed January 11, 1919. Serial No. 270,713.

To all whom it may concern:

Be it known that I, PATRICK J. GRIFFIN, a citizen of the United States, and a resident of Dorchester, in the county of Suffolk, 5 State of Massachusetts, have invented an Improvement in Propellers, of which the following description, in connection with the accompanying drawings, is a specification, like characters on the drawings representing 10 like parts.

This invention relates to propellers which are adapted by rotation in a fluid medium to advance the structure on which they are mounted. While not limited thereto, my 15 invention is more particularly adapted for use on airplanes and similar craft wherein the propeller works in air.

My invention will best be understood by reference to the following description of an 20 illustrative embodiment thereof taken in connection with the accompanying drawings wherein:

Figure 1 is a side elevation of an airplane propeller constructed in accordance with my 25 invention;

Fig. 2 is an end view thereof; and

Figs. 3 and 4 are sections on the lines 3—3 and 4—4, respectively, of Fig. 1.

For convenience in the following description, I shall refer specifically to the propeller 30 as one for use on aircraft.

Referring to Fig. 1 of the drawings, I have there shown as an example of my invention a propeller of composite structure; 35 although my invention is not limited thereto. In such a composite propeller I may utilize as a part thereof a wooden propeller 5 of the type now commonly utilized on airplanes and embodying such features of form 40 and proportion as have been empirically determined to be most efficient. Such a propeller embodies a hub 7 secured in desired manner on the shaft 9, from which hub radiate blades 11, usually lenticular in section as shown in Fig. 3, and usually two in 45 number as shown. The proportions, form and pitch of such a propeller have been determined by practice and I may follow the usual custom in these points. Conveniently, 50 however, the propeller 5 may be smaller than a propeller of the usual type adapted to develop a similar thrust for reasons which will hereinafter appear.

In accordance with my invention I utilize 55 auxiliary blades, as 13, which are hubless

and are carried by and supported at a fixed distance from the main blades 11. From analogy to the case of aerofoils I may make this distance once and a half the width of the blade, although this proportion may be 60 suitably varied. In the present embodiment of my invention I have shown two sets of auxiliary blades 13 and 15, one set on each side of the main blades, but for the present I will confine my description to the blades 65 13 since but one set of blades may be used, although I prefer to use two sets, as shown in the drawings. The blades 13 may be conveniently formed of metal of substantially uniform thickness and are disposed 70 substantially parallel to the adjacent surface of the blade 11. The blade 13 is similar in form to the outer portion of the blade 11 but differs therefrom in having no hub and conveniently may be made to project beyond the tip of the main blade, as indicated in Fig. 2. Otherwise described, it may be said that the auxiliary blade 13 has throughout its surface substantially the same angle 75 or pitch, which is that of the outer or most effective portion of the main blade 11, and, being hubless, need have no portion corresponding to the less effective inner portion 80 of the main blade.

The auxiliary blade 13 may be supported 85 in position relatively to the blade 11 by any suitable means, but preferably by supports 17 which may be of stream line form as shown in Fig. 4 and which are desirably curved in such manner that they form segments of cylindrical surfaces centered on the axis of rotation. Thus, when the propeller rotates the supports do not offer a resistance but, in fact, have advantageous functions hereinafter to be referred to. The 90 supports may be secured in place in any desired manner but by way of example in the composite propeller shown for purposes of illustration I have disclosed bands 19 shrunk about the blades 11 and conveniently pinned thereto at 21 to resist separation by the centrifugal force of the rotating propeller. The supports 17, which are conveniently of metal, may be secured to the bands 19 by welding, 95 brazing or some similar process and are integral or integrally connected with the blades 13.

To resist the pull of centrifugal force on the blades 13, they may be stayed to the propeller shaft 9 at their inner ends and herein 110

I show means providing for mutual support of the blades comprising a relatively small connecting stay 23 between their inner ends which may be apertured, as indicated in Fig. 5, 2, to receive the propeller shaft, which affords the stay a support. It will be understood, however, that the connecting stay 23 is not similar to and does not correspond to the hub 7 to which the main blades are secured but that the auxiliary blades are supported primarily from the main blades 11.

The blades 15 are disposed on the opposite side of the main blades 11 in a similar manner, preferably symmetrically to the 15 blades 13, thus providing a desirably balanced structure. Conveniently the auxiliary blades may be dished, as indicated in Fig. 3, the dishing being such as to present the concave sides forwardly of the normal 20 direction of rotation, herein rearwardly since the drawings are assumed to represent a tractor screw.

As best indicated in Fig. 2 and in Fig. 3, wherein the axial line is horizontal, the 25 blades of each set are preferably offset axially or staggered or echeloned. Thus, viewing Fig. 2, in the counterclockwise rotation of the propeller the blades do not come to a given angular position and enter the air 30 simultaneously but one after the other, and preferably this staggering is so arranged that the hindermost blade in the direction of travel of the structure on which the propeller is mounted, herein the blade 15, will 35 be angularly in advance of the relatively leading blade 11 which in turn is in advance of the blade 13. By the staggering of the blades the plurality of blades operates simultaneously on a larger area than any 40 single blade, as will be clearly understood from reference to Fig. 2; and by the preferable arrangement of this staggering as described, each blade as it rotates enters air which is less disturbed from the action 45 of the relatively leading blade than would otherwise be the case.

A prime advantage of a propeller constructed in accordance with my invention lies in the increase of effective surface without corresponding increase in effective surface leading to difficulties in construction and in operation. It has been demonstrated that the outer portion of a propeller adjacent the tips of the blades does the major 55 part of the work. The inner portion adjacent the hub is ineffective and it, together with the hub, in fact constitutes a drag on the mechanism. Adjacent the axis of the propeller there is a dead body of air which 60 retards the motion of the aircraft and through which the large hub of the propeller must be dragged. By the use of the auxiliary, hubless blades, as described, the area adjacent the outer circumference of the 65 propeller is markedly increased without cor-

responding increase at the hub. Thus, the driving power is greater while the retarding effect is the same. In a simple propeller the same increase in surface could not be obtained from an increase in the size of the blades 11 without a corresponding increase in the size of the inner parts, with a marked increase in weight and the introduction of many constructional difficulties.

Careful tests with a propeller constructed 75 in accordance with my invention have indicated that it is of greater efficiency than ordinary propellers with a single set of blades, in that there is less slip and the propeller better grips the air. However, disregarding this increase in efficiency, it will 80 be apparent that if the same power were to be developed, my propeller might be made smaller in over-all dimensions and could rotate at a slower rate, since the working 85 surface is greater. Terrific strains are at present imposed on airplane propellers due to their great size and excessive speed, and as the length of the blade is increased the linear speed of the parts rapidly increases 90 and the propellers tend to tear themselves to pieces. The possibility of increasing the effective area of the blades without undue increase in the speed thereof and with an additional limitation of speed, both linear 95 and rotative, eliminates many structural difficulties presented by the present type of propeller when designed to develop great power.

I have stated that careful tests appear to 100 show a greater efficiency in a propeller of the type herein disclosed in that it obtains a better grip upon the air and has less slip. I state this as an empirical fact and do not wish to be bound to any particular theory 105 as to the action. It seems probable, however, that the following statements are correct. It has been shown in connection with lifting surfaces on airplanes that the same lifting power can be obtained from super- 110 posed planes as can be obtained from a larger single plane and with less friction provided the planes are made suitably narrow. A similar absence of retarding friction is probably present in my propeller. 115 In biplanes it is stated that there is a disadvantage in interference between the currents of air between the upper and lower planes, but it is my belief that in a propeller as shown this interference, if it exists, is 120 not a disadvantage but permits a more effective grip of each rotating blade upon the air. Referring to Fig. 1, it will be noted that a portion of the blade 13 acts against the body of air confined on either side by 125 the segmental supports 17. It is my belief that this insures a better grip of the blades upon the air.

The supports 17, however, have an additional function in that while they offer little 130

substantial resistance to the regular rotation of the propeller on account of their lying in the circular orbit through which the blades rotate, they do resist side-slip and nose-dive as they have comparatively broad surfaces which are moved laterally through the air if the vehicle swerves.

Having thus described in detail a single preferred embodiment of my invention, the principles illustrated thereby which I consider new and desire to secure by Letters Patent I shall express in the the following claims:—

1. In a screw propeller a hub having a plurality of radiating blades and auxiliary hubless blades carried by said first blades in spaced relation thereto.

2. In a screw propeller a hub having a plurality of radiating blades and auxiliary hubless blades carried by said first blades in spaced relation thereto, the auxiliary blades being similar in form and substantially parallel to the adjacent surfaces of the main blades.

3. In a screw propeller a hub having a plurality of radiating blades and auxiliary hubless blades carried by said first blades in spaced relation thereto, the auxiliary blades being similar in form and substantially parallel to the adjacent surfaces of the main blades but offset relatively thereto axially of the propeller.

4. In a screw propeller a hub having a plurality of radiating blades and auxiliary blades similar in form to the outer portions of the main blades and homologously supported thereby in spaced relation thereto.

5. In a screw propeller a hub having a plurality of radiating blades and auxiliary blades similar in form to the outer portions of the main blades and homologously supported thereby in spaced relation thereto, said auxiliary blades extending radially beyond the main blades.

45 6. In combination, a propeller shaft, a blade-carrying hub mounted rigidly thereon, and a plurality of blades of which some are integral with or rigidly mounted on said hub and others are rigidly affixed to said first-named blades and not attached to said hub.

7. The combination of a hub and a screw propeller blade extending therefrom in a plane substantially at right angles to the axis of the propeller shaft and ending at its tip in such angle as is best adapted to secure the most effective grip upon the element in which the propeller turns, and an auxiliary blade fixedly secured on said first-named blade and having throughout its length substantially the same angle of inclination to the axis of rotation as the tip of said first-named blade.

8. In a screw propeller a hub having a

plurality of radiating blades, auxiliary hubless blades fixedly supported beside the outer portions of the main blades, the supporting means comprising connecting supports in the form of cylindrical segments centered on the axis of rotation.

9. In a screw propeller a hub having radiating blades, auxiliary hubless blades and means for supporting each auxiliary blade in spaced, substantially parallel relation to a main blade comprising a pair of connecting supports in the form of cylindrical segments centered on the axis of rotation.

10. In a screw propeller a hub having a plurality of radiating blades, auxiliary hubless blades fixedly supported beside the outer portions of the main blades, the supporting means comprising connecting supports in the form of cylindrical segments centered on the axis of rotation and disposed inwardly of the tips of the blades.

11. A screw propeller comprising radiating sets of homologous blades, the elements of each set being serially disposed in the direction of travel of the driven structure and relatively offset axially, each following blade being, in the normal rotative sense, in advance of the relatively leading blade.

12. A screw propeller having a main blade and an auxiliary blade carried thereby in spaced relation thereto, extending outwardly beyond the tip of the main blade and terminating inwardly at such distance from said shaft that it does not extend into the area of disturbance in which little or no propulsive effect is gained.

13. A propeller having a hub, a main blade projecting therefrom, an auxiliary blade similar to the outer portion of the main blade and supported thereby in spaced relation thereto and means to stay the auxiliary blade to the propeller shaft against centrifugal pull.

14. A propeller having a hub, a pair of blades projecting therefrom, auxiliary blades similar to the outer portions of the main blades supported thereby in spaced relation thereto and a connecting stay between the inner ends of the auxiliary blades.

15. A propeller having a hub, a pair of blades projecting therefrom, auxiliary blades similar to the outer portions of the main blades supported thereby in spaced relation thereto and a connecting stay between the inner ends of the auxiliary blades, said stay receiving and being supported by the propeller shaft.

16. A screw propeller having a hub with projecting blades and auxiliary hubless blades carried by the main blades in spaced relation thereto, said auxiliary blades being dished.

17. A screw propeller having a hub with projecting blades and hubless auxiliary

blades supported by the main blades forward and back of the same in fixed relation thereto.

18. A screw propeller having a hub with 5 projecting blades and hubless auxiliary blades supported by the main blades forward and back of the same in fixed relation

thereto by means of supports substantially in the form of cylindrical segments centered on the axis of rotation.

10

In testimony whereof I have signed my name to this specification.

PATRICK J. GRIFFIN.
